UNITED STATES PATENT OFFICE.

OWEN SINGER, OF PORTLAND, OREGON.

PUMP.

1,150,826.

Specification of Letters Patent. Patented Aug. 17, 1915.

Application filed December 24, 1913, Serial No. 808,556. Renewed January 18, 1915. Serial No. 3,001.

To all whom it may concern:

Be it known that I, OWEN SINGER, a citizen of the United States, residing at Portland, in the county of Multnomah and State 5 of Oregon, have invented certain new and useful Improvements in Pumps, of which the following is a specification.

This invention pertains to pumps, and particularly to that form of pumps known 10 as chain pumps, and has for its object to increase the relative area of the lifting elements in such pumps. I accomplish this object by means of the structure illustrated in the accompanying drawing, in which—

15 Figure 1 is a side elevation, partly in section, with the intermediate portion broken away, showing the method of mounting and the manner of operating my improved pump. Fig. 2 is an end view of the cylindrical tube 20 constituting the body of the pump, showing a plan view of the lifting disk in working position. Fig. 3 is an elevation of a fragment of the pump chain, showing an edge view of a lifting disk.

25 Referring to the numerals on the drawing, 1 designates a lifting disk stamped from sheet metal of a diameter to fit loosely in the cylindrical tube 8 and to move freely therein with the chain to which it is attached.

30 The cylinder 8 is fixed in vertical position by means of any suitable support, such as the frame 10, with its lower end in communication with the water supply. It is secured by means of the strap 9 at the upper end; 35 and from an extension thereon is supported a column, or riser 7 which at its lower end rests upon a suitable extension from the frame 10. At the upper end of the riser 7 is mounted the shaft 5 which carries a 40 sprocket wheel 6. The diameter of this wheel is such that its periphery or teeth will stand directly above the central point in the cylinder 8, so that a sprocket chain working thereon will move along the longitudinal 45 center of the cylinder.

Upon a suitable bracket 13 supported from the lower end of the cylinder is mounted another sprocket wheel 6, on a shaft 5. This wheel is mounted in vertical alinement 50 with the upper wheel, and positioned so as to deliver the chain at the lower end of the cylinder, in its longitudinal center.

55 At suitable intervals along the chain is secured a disk 1 to a link 2 thereof. Each of these disks has stamped from one side a recess 1^a, sufficiently wide to receive the rim of

the sprocket wheels, and extending well toward the center, so that it will move freely with the chain without interference with the wheels. 60

From suitable points in the central portion of each disk are stamped up ears 4, in position to bear against the respective sides of a link 2 of the chain which is inserted into the central opening 1^b and to which it is 65 fixed by means of rivets 4.

Power will be applied to the chain through the upper shaft 5, but since the disks 1 each have the opening, 1^a, they can not carry water up the vertical cylinder, unaided. 70 have, therefore, placed within the lower end of the cylinder, a block 15 of suitable cross sectional area to fill the recess 1^a, and of a length greater than the distance between two of the disks, so that at least two of the disks 75 at the lower end of the cylinder will always be closed to prevent the return of the water carried up. This block is secured in place by means of screws 14, or in other suitable manner; and it is beveled at its lower portions 15^a to prevent the accidental engagement of the disks thereon.

By means of this structure, I am enabled to use a cylindrical tube, while heretofore half-round tubes have been employed. I 85 thus approximately double the capacity of the pump without materially increasing its cost.

Having described my invention, what I 90 claim, is:—

1. A pump comprising in combination a cylinder, a sprocket wheel mounted at each end of the cylinder, in alinement with each other, their peripheries being alined with the longitudinal center of the cylinder, a 95 sprocket chain mounted for movement on said wheels, disks fixed transversely on said chain loosely fitted in said cylinder, each of said disks being provided with a recess, and means in the lower portion of the cylinder 100 for temporarily closing said recesses.

2. A pump comprising in combination a cylinder, a sprocket wheel mounted at each end of the cylinder, in alinement with each other, their peripheries being alined with the longitudinal center of the cylinder, a sprocket chain mounted for movement on said wheels, disks each having a recess in one side adapted to receive the rim of a sprocket wheel, fixed transversely by the central portion upon said chain, and an oblong block, 105 conforming in cross section to said recess 110

fixed in the lower portion of the cylinder in position to engage in each of said recesses as the chain moves through the cylinder.

3. A lifting element for pump chains, comprising a disk having a recess cut from one side extending well toward the center thereof, and supporting ears stamped up from the center of the disk to stand at right angles to the face thereof.

10 4. As a new article of manufacture a pump chain comprising a series of oblong

links, disks, each stamped to form a central opening adapted to receive a link of said chain, an ear formed by the stamping of said opening rising against each side of the 15 link, and means for securing it thereon.

In testimony whereof I affix my signature in presence of two witnesses.

OWEN SINGER.
